Primary Examiner — Robert M Spear(74) *Attorney, Agent, or Firm* — Knobbe, Martens, Olson & Bear, LLP(57) **CLAIM**

The ornamental design for a screen for preventing bugs and debris from entering a beverage container, as shown and described.

DESCRIPTION

FIG. 1 is a perspective view of the screen for preventing bugs and debris from entering a beverage container.

FIG. 2 is a side view of the screen for preventing bugs and debris from entering a beverage container. All four side views (front, rear, left and right) are identical to the side view of FIG. 2.

FIG. 3 is a top view of the screen for preventing bugs and debris from entering a beverage container; and, FIG. 4 is a bottom view of the screen for preventing bugs and debris from entering a beverage container.

The broken lines in the drawings represent unclaimed environmental subject matter and form no part of the claim.
